UNITED STATES PATENT OFFICE.

DONALD R. MACBAIN, OF CLEVELAND, OHIO.

AIR-BRAKE SYSTEM.

1,378,365.

Specification of Letters Patent. Patented May 17, 1921.

Application filed October 18, 1919. Serial No. 331,609.

To all whom it may concern:

Be it known that I, DONALD R. MACBAIN, citizen of the United States, residing at 1921 E. 97th St., city of Cleveland, county 5 of Cuyahoga, State of Ohio, have invented certain new and useful Improvements in Air-Brake Systems, of which the following is a specification.

This invention relates to an engineer's 10 auxiliary brake controlling system, its object being to provide means whereby an engineer may control the setting of the brakes upon the several cars of a train even though one or more angle cocks in the train line is, 15 or are, closed.

The system constituting the subject matter of the present invention is intended to operate in conjunction with the standard 20 automatic air-brake systems commonly in use. It is well known that in these systems the setting of the brakes is effected by a reduction in pressure in the train line. It is a known fact that many serious and destructive wrecks have been occasioned by 25 one or more of the angle cocks of the train line being inadvertently left closed. The present invention, therefore, aims to provide means through which the engineer may 30 vent the train line in the rear of the closed angle cocks, the setting of the brakes being thereafter effected by the usual service cylinder and auxiliary reservoir pressure of the standard automatic brake mechanism.

Broadly stated the invention contemplates 35 providing a by-pass around the usual reducing valve of the signal line of the train and locating in said by-pass a stop cock accessible from the engineer's seat, so that if the engineer finds that his control of the 40 brakes is interfered with by a closed angle cock he may, by opening the stop cock in the by-pass, throw the full main reservoir pressure into the signal line, this increase of pressure above normal in the signal line 45 acting upon pistons in auxiliary cylinders to open the conductor's valve in the several cars and bring about the necessary reduction in pressure in the train line to cause the brakes on said cars to be set in the usual and 50 well known way.

The invention further contemplates the provision of means for conducting the increased pressure in the signal line to the service cylinders of the several cars after 55 the conductors' valves have been operated as set forth to thereby augment the pressure

in said cylinders, this feature being valuable if the air pressure in the brake system has become lessened to an appreciable degree as a result of the angle cock or cocks 60 being closed.

Further objects and advantages of the invention will be set forth in the detailed description which now follows.

In the accompanying drawings— 65

Figure 1 is a diagrammatic view illustrating the mechanism upon an individual car of a train;

Fig. 2 is a vertical section through an auxiliary cylinder hereinafter described; 70

Fig. 3 is a vertical section through a special valve used in the connecting pipe between the triple valve and the service cylinder; and

Fig. 4 is a diagrammatic view illustrating the by-pass around the reducing valve 75 of the signal pipe.

In the drawings 5 designates the main reservoir, 6 the signal pipe and 7 a reducing valve by which the normal one hundred thirty pounds pressure of the main reservoir is reduced to the usual fifty pounds pressure in the signal pipe. A by-pass 8 leads around the reducing valve and has a stop cock 9 located in its length, said stop 85 cock being located in such proximity to the engineer's seat that the engineer may readily reach the same. Referring now to Figs. 1 and 2, 6^a designates an extension from the train signal pipe which leads to the bottom of an auxiliary cylinder 10, it being understood that the structure of Figs. 1 and 2 is duplicated upon each car of the train. Slidable within each of the auxiliary cylinders 10 is a heavily weighted piston 11 which carries a valve disk 12 at its 90 bottom that is adapted to have a seating upon a valve seat 13 so that under normal conditions the extension 6^a of the signal pipe will be closed and the normal line pressure 100 will be maintained therein, but if, as previously explained, the pressure in this signal line is suddenly increased by the opening of the stop cock in the by-pass by the engineer this increased pressure will act 105 to force the piston 11 upwardly and through piston rod 14, links 15 and pivoted lever 16

act upon an auxiliary conductor's valve 17 to vent the train line through air-brake pipe 18 in the same manner that said line would 110 be vented by the opening of the usual conductor's valve 19. It is well known that

when the train line is vented and the pressure is reduced a triple valve 20 functions to permit pressure fluid to pass from an auxiliary reservoir, not shown, to the service cylinder 21 of the car. However, it is possible that, by reason of an angle cock having been closed, inadequate pressure will exist in the auxiliary reservoir and to provide for this contingency I provide a special valve 22. By referring to Fig. 3 it will be seen that this special valve comprises a casing 24 having valve seats 25 and 26 adapted to be closed by the valve disks 27 and 28 respectively. These valve disks are mounted 15 upon a stem 29 and said stem carries a piston 30 that is mounted in a cylinder 31. The cylinder 31 is threaded at 32 into engagement with the casing 24. A spring 33 tends to elevate the piston 30. A cap 34 is threaded into the upper end of the cylinder 31 and this cap is tapped for the reception of a pipe 35 that leads to the side of the auxiliary cylinder 10 and has connection with said cylinder 10 at a point somewhat above 25 the bottom of the cylinder. Consequently after the piston 11 has been moved upwardly a predetermined distance it uncovers the port 36 to permit the full main reservoir pressure to pass through pipe 35 and enter the upper 30 portion of the cylinder 31 where this pressure acts upon the piston 30 and forces this piston downwardly against the action of the spring 33, thereby seating disk 28 upon seat 26 and unseating disk 27 from seat 25. It 35 is to be noted that the stem 29 is tubular throughout the upper portion of its length as indicated at 37 and that the bore thereof communicates with lateral port 38. When the piston 30 moves downwardly under the 40 influence of the main reservoir pressure, the ports 38 are brought into communication with the chamber 24' of the valve casing 24, and the main reservoir pressure may then pass through the port 38, chamber 24' and 45 the right hand portion of the pipe 23, Fig. 1, to the service cylinder, thereby insuring the necessary degree of pressure in said service cylinder to effectively set the brakes.

As soon as the engineer closes the stop 50 cock in the by-pass and no additional pressure is supplied to the signal line except what passes the reducing valve the pressure in the signal line is quickly restored to normal by leakage through a minute port 40 formed in the bottom of the auxiliary cylinder 10.

It will be understood that the weight of 60 the piston 11 is designedly made such as to maintain the proper degree of pressure in the signal line. In other words, the weight of this piston is such that it will not be lifted until the pressure in the signal line exceeds normal.

It is manifest that instead of making this 65 piston a weighted one a spring could be

used, though I prefer the construction shown. The disk 27 and seat 25 constitute a valve structure which prevents pressure in the pipe 23, during the ordinary application of the brake, from leaking back through 70 pipe 35 to the auxiliary cylinder 10.

It is within the scope of my invention to utilize a separate pressure line, instead of the signal line, if desired, though the utilization of the signal line in the manner set 75 forth renders the installation of this system a very simple and economical matter.

It is to be understood that the invention is not limited to the precise construction set forth but that it includes within its purview 80 whatever changes fairly come within either the terms or the spirit of the appended claims.

Having described my invention, what I 85 claim is:

1. The combination with an automatic air-brake system operable upon reduction of pressure in the train line, of individual pressure operated venting elements in each car for said train line having connection with 90 the signal line of the train and means controllable from the engine cab for creating a greater than normal pressure in said signal line to thereby cause the actuation of the individual venting elements. 95

2. The combination with an automatic air-brake system operable upon reduction of pressure in the train line, of individual pressure operated venting elements in each car for said train line, a signal line connected to 100 the pressure operated elements, means for preventing the operation of said elements by the normal pressure of the signal line and means controllable from the engine cab for creating a greater than normal pressure in 105 the signal line to thereby operate said venting elements.

3. The combination with an automatic air-brake system operable upon reduction of pressure in the train line, and including a 110 main reservoir upon the engine, a signal line connected to said reservoir through a reducing valve, a by-pass leading from the main reservoir to the signal line around said reducing valve, a stop cock in said by-pass, individual venting elements for the train line in the several cars, pressure operated actuating means for the venting elements connected to the signal line which are not operable under the normal pressure of the signal line but operate upon the introduction of excess pressure to said signal line from the main reservoir. 115

4. The combination with an automatic air-brake system operable upon reduction of 125 pressure in the train line, of individual venting elements in each car for said train line and, actuating means for said venting elements comprising cylinders pistons operable therein, a pressure line leading to the cylinder. 130

ders beneath said pistons and valvular means upon said pistons for closing said pressure line until the pressure therein exceeds a predetermined degree.

5 5. The combination with an automatic air-brake system operable upon reduction of pressure in the train line and including individual train line venting elements in the several cars and individual service cylinders upon said cars, of pressure operated members for actuating the venting elements, a pressure line controllable from the engine for supplying pressure to said members and means for conducting the actuating pressure

10 from said members to the service cylinders.

15 6. The combination with an automatic air-brake system operable upon reduction of pressure in the train line and including individual venting elements in the several cars

20 of a train and also including the usual service cylinders and triple valves upon the several cars, of a piston operated valve disposed in the connection between the service cylinder and the triple valve and operable

25 under pressure to close that part of said connection leading to the triple valve and to admit the actuating pressure to the service cylinder, auxiliary cylinders in the several cars, pistons therein, said individual train

30 line venting elements adapted to be actuated by the movement of said pistons, a connection between each of said pistons and the corresponding pressure actuated valve for conducting pressure from the former to the

35 latter, a signal line leading to the auxiliary cylinders, means for maintaining the signal line closed with respect to said pistons until the pressure in the signal line exceeds normal and means controllable from the engine

40 cab for admitting a greater than normal pressure to the signal line to thereby actuate the pistons in the auxiliary cylinders to operate the train line venting elements and to thereafter admit such pressure to the service

45 cylinders.

7. The combination with an automatic

air-brake system operable upon reduction of pressure in the train line, of individual train line venting elements in each car, auxiliary cylinders in the several cars, pistons in said

50

cylinders the movement of which operates said venting elements, a signal line having connection with the several cylinders, means carried by the pistons in the auxiliary cylinders for maintaining the signal line closed

55

with respect to said auxiliary cylinders until the pressure in said signal line exceeds normal, a main reservoir to which the signal line is connected, a by-pass, a controlling valve in said by-pass, a connection between

60

the signal line and the main reservoir including a reducing valve whereby the pressure may be maintained at normal in the signal line through the medium of the reducing valve or may be increased to considerably

65

above normal through said by-pass, said air-brake system including the usual cylinders, triple valves and connections therebetween upon the several cars, a piston operated valve in each of the connections between the

70

triple valves and the service cylinders of the several cars and a connection between said piston operated valve and the auxiliary cylinders whereby when the pressure in the signal line is increased to greater than normal

75

the pistons in the auxiliary cylinders will be actuated to operate the venting elements in the several cars and said operating pressure will thereafter be conducted through said connections to the piston operated valve, the

80

latter acting under the influence of said pressure to cut off communication between the auxiliary cylinders and the triple valves and establish communication between the auxiliary cylinders and the service cylinders.

85

In testimony whereof the foregoing specification is signed in the presence of two witnesses.
